UNITED STATES PATENT OFFICE.

ARTHUR L. JOHNSON, OF OAK PARK, ILLINOIS.

DESIGN FOR A CHAIR BACK.

Application filed November 10, 1927. Serial No. 24,065. Term of patent 14 years.

To all whom it may concern:

Be it known that I, ARTHUR L. JOHNSON, of Oak Park, in the county of Cook and State of Illinois, have invented a new, original, and ornamental Design for a Chair Back, of which the following is a specification, reference being had to the accompanying drawing, forming a part thereof.

tion being indicated by line 2—2 of Figure 1, and

Figure 3 is a longitudinal section, the section being indicated by line 3—3 of Figure 2.

I claim:

The ornamental design for a chair back, as shown.

In testimony that I claim the foregoing I have hereunto set my hand at Oak Park, in the county of Cook and State of Illinois.

ARTHUR L. JOHNSON.
